[57] CLAIM

The ornamental design for a microphone, as shown and described.

DESCRIPTION

FIG. 1 is a front, top and right side perspective view of a microphone showing our new design;

FIG. 2 is an enlarged view of the detail circled on FIG. 1;

FIG. 3 is a rear, top and left side perspective view of FIG. 1;

FIG. 4 is a top plan view thereof;

FIG. 5 is a right side elevational view thereof; the left side view being a mirror image;

FIG. 6 is a front elevational view thereof;

FIG. 7 is a rear elevational view thereof;

FIG. 8 is a front, top and right side perspective view of a second embodiment of FIG. 1;

FIG. 9 is an enlarged view the detail circled on FIG. 8;

FIG. 10 is a rear, top and left side perspective view of FIG. 8;

FIG. 11 is a top plan view thereof;

FIG. 12 is a right side elevational view thereof; the left side view being a mirror image;

FIG. 13 is a front elevational view thereof; and,

FIG. 14 is a rear elevational view thereof.

The bottom views of embodiments 1 and 2 form no part the claimed design.

The broken line showing the microphone cord on FIGS. 1, 3-5, 7-8, 10-12 and 14 is for illustrative purposes only and forms no part the claimed design.

The broken line showing on FIGS. 1-2 and 8-9 indicate the detailed area.
